D. CASWELL

OIL BURNER

Filed March 24, 1926

UNITED STATES PATENT OFFICE.

DOMINICK CASWELL, OF WATERTOWN, NEW YORK.

OIL BURNER.

Application filed March 24, 1926. Serial No. 97,098.

This invention relates to improvements in oil burners, designed for use in connection with furnaces, steam generators, cooking and heating appliances, and has for its object to 5 provide a liquid fuel burner that is novel, simple and compact in construction, by which the maximum heat may be produced by the consumption of a minimum of fuel, and which burns the fuel without any waste 10 or odor. A further object is to provide a burner of the class, which receives the fuel by gravity, and in which the oxygen required to effect the satisfactory combustion of the fuel is supplied by a novel manifold, which 15 collects air from points below the plane of the fuel nozzle or jet, and which discharges the air at a common plane above and concentric to the flaring flame of the burning oil, the said manifold being so positioned relatively to the plane of combustion as to facilitate the preheating of the air before the latter mingles with the flame. A further object 20 is to provide a novel adjustable deflector, which serves the dual purpose of spreading the flame as it ascends from the single jet of the burner, and at the same time similarly deflects and spreads the descending oxygen in a manner to effect the union of the said 25 elements about midway between the discharge opening of the manifold and the nozzle or jet. And a further object is to provide a plurality of stationary heat-and-flame deflectors, which are supported by the manifold and tend to deflect the products of combustion horizontally beyond the manifold in 30 all directions.

I attain these objects by the means set forth in the detailed description which follows, and as illustrated by the accompanying 40 drawing, in which—

Figure 1 is a top plan view of the complete device. Fig. 2 is a front side elevation of the same. Fig. 3 is a top plan view of the base with the manifold removed. Fig. 4 is 45 a vertical section, taken on line 4—4 of Fig. 1. Fig. 5 is a horizontal section, taken on line 5 of Fig. 4. And Fig. 6 is a fragmentary section, showing dampers for controlling the flow of the air through the arms of the manifold.

In the drawing, 2 represents a hollow rectangular base, comprising a relatively large air chamber, which is preferably open

at its top and bottom ends, the latter adapted to rest upon the grates, in case the burner is disposed within the fire-pot of an ordinary hot-air furnace, as indicated by the base line 2' in Fig. 2. Wherever the burner is installed, it is essential that the bottom of base 2 be kept open for the free entrance of air. 55 The open top 2^a of the base 2 is preferably closed by a plate or bed 3, which is formed with a central depressed portion 3', whose top preferably sinks below the plane of the plate, for providing a relatively broad shallow fuel pan 3^a. The fuel oil α may be applied to the pan 3^a by a pipe 4, which connects with an aligning opening or port 3^b, best seen in Fig. 4, the said port being concentric to a circular moat or recess 3^c, which 60 collects the oil α fed by the said port. Any excess oil that escapes from the recess 3^c may drain off through an over-flow opening 3^d (see Figs. 3 and 4). The oil α when first turned on is allowed to substantially fill the 65 annular recess 3^c. A feed valve (not shown) is usually disposed in the pipe 4 and said valve is preferably adjusted to supply the required amount of fuel during a heating period. The plate 3 is also provided near its 70 four corners with similar angular air openings as 3^e, the said openings being skirted by upturned flanges or ribs 3^f, the said ribs being arranged to provide shallow sockets that surround the clear openings 3^e. 75 5 represents the air manifold or spider which is preferably cast in one part, in the form of the letter X, having four hollow arms as 5', of equal length, whose free ends curve downwardly and are 80 formed with continuous horizontal shoulders 5^a, that surround reduced portions 5^b, the latter being loosely inserted in the openings 3^e of plate 3. The air received from the chamber 2 flows upwardly and thence 85 convergingly through the arms 5' and discharges downwardly into a common central opening 5^c that aligns axially with the nozzle or jet 3^b and the annular recess 3^c. The arms 5' and the opening 5^c are preferably 90 entirely unobstructed so that the air may be freely and copiously supplied to the combustion zone A which lies between the plate 3 and the underside of the manifold, as best 95 shown in Fig. 4. The air flowing from the 100 manifold 5 is preferably controlled by a 105

deflector or baffle, which comprises a conical member or body 6, shaped like a spinning top, the said deflector being supported pendently by a threaded rod 6', which is disposed axially in the opening 5^c and passes upwardly through a perforation 5^a, and is adjustably held in place by nuts 6^a, which rest upon the top of the manifold. The pointed lower end of the member 6 normally registers with and may enter the fuel port 3^b, and when the said member is raised and lowered it tends to regulate the flow of fuel oil into the recess or moat 3^c. By this arrangement, an additional feed regulator is afforded, which facilitates finer and more accurate control of the liquid fuel, as well as the heating capacity of the burner. The conical top 6^b of member 6 tends to deflect the air radially, as shown by the arrows 7, while the tapered portion 6^c of said member tends to deflect the flame resulting from the burning of the oil in the recess 3^c, as indicated by the arrows 7' (see Fig. 4). This effects the commingling of the oxygen and the flame at substantially the plane indicated by the broken horizontal line 7^a (see Fig. 4) and complete combustion ensues. The products of the combustion tend to rise after being deflected radially by the baffle 6, and in order to effect the even and suitable spreading of the hot products, I provide a number of angular stationary heat-and-flame deflectors, which comprise similar substantially V-shaped webs 8, the latter being cast with the arms 5' of the manifold. The deflectors 8 together with the arms 5' form a substantially square deflecting field (see Figs. 1 and 5), that is co-extensive with the combustion zone A and tends to distribute or deflect the flame and heat radially beyond the extremities of the manifold 5 and the plate 3. The heat generated in the zone A rises and envelops the curved portions of the several arms 5' and tends to preheat the air flowing from the chamber 2 toward the said zone and accordingly increases the heating capacity of the burner. The adjustment of the deflector 6 at its widest practical range, as indicated by the full and dotted lines in Fig. 2, enables the operator or user, to vary the capacity of the heater to suit almost any requirement. Dampers as 9, shown in the fragmentary section, in Fig. 6, may be applied to the several arms 5' of the manifold, for apportioning the air to the fuel oil, in a well-known manner. The heating capacity of the burner may be enlarged or lessened by the raising and lowering of the deflector 6.

60 The present burner is essentially non-vaporizing, that is to say, the kerosene or other fuel oil is fed directly to the annular recess 3^c in the bottom of the pan 3^a, where it is ignited and burned without any of the usual vaporizing means. A strand or two of can-

dle-wick 9', is usually coiled around the nozzle 3^b (see Fig. 4) and tends to effect the ready, as well as the steady burning of the oil x , held by the recess 3^c.

Having thus described my invention, what I claim, is—

1. In an oil burner, a hollow base having a rectangular top formed with an annular recess surrounding a nozzle adapted to be filled with fuel oil, and having openings near its four corners, an X-shaped hollow manifold rising from said top, the arms of the manifold adapted to receive air from the openings in said top and to discharge the air above said nozzle, and a conical deflector interposed between the manifold and said nozzle adapted to regulate the flow of fuel oil toward said recess and to control the spreading of the flame. 75

2. An oil burner comprising a hollow base having an open bottom and a top provided with an air opening, said top having a fuel port therein, an air conduit registering with the air opening and having its outlet end terminating above and spaced from said fuel port, and a double cone-shaped mixing member disposed intermediate the fuel port and the outlet end of the air conduit to cause the fuel and air to commingle at a point intermediate the fuel port and the air outlet. 80

3. An oil burner comprising a hollow base having an open bottom and a top provided with series of air openings, said top having a centrally located fuel port therein, a cruciform shaped conduit having its free ends registering with the air openings and its opposite ends conjointly forming an air opening above and spaced from said fuel port, and a double cone-shaped mixing member disposed intermediate the fuel port and the opening in the conduit to cause the fuel and air to commingle at a point intermediate the fuel port and the air outlet. 100

4. An oil burner comprising a hollow base having an open bottom and a top provided with a series of air openings, said top having a centrally located fuel port therein, a cruciform-shaped conduit having its free ends registering with the air openings and its opposite ends conjointly forming an air opening above and spaced from said full port, V-shaped heat deflecting webs interposed between the arms of the cruciform-shaped conduit, and a double cone-shaped mixing member disposed intermediate the fuel port and the opening in the conduit whereby to cause the fuel and air to commingle at a point intermediate the full port and the air outlet and to contact with the heat deflecting baffle to heat the incoming air within the cruciform-shaped conduit. 110

5. An oil burner comprising a hollow base having an open bottom and a top provided with a series of air openings, said top having a centrally located fuel port therein, a 120

cruciform-shaped conduit having its free ends registering with the air openings and its opposite ends conjointly forming an air opening above and spaced from said fuel port, and a double cone-shaped mixing member disposed spaced from said air opening and having its lower end disposed in said

fuel port to regulate the flow of fuel, said mixing member being adapted to cause the fuel and air to commingle at a point intermediate the fuel port and the air outlet. 10

In testimony whereof I affix my signature.

DOMINICK CASWELL.
